C. H. SCHLOTH

DANCING TOY

Filed March 15, 1924

Patented Aug. 4, 1925.

1,548,101

UNITED STATES PATENT OFFICE.

CARL HERMAN SCHLOTH, OF MANCHESTER, NEW HAMPSHIRE.

DANCING TOY.

Application filed March 15, 1924. Serial No. 699,498.

To all whom it may concern:

Be it known that I, CARL HERMAN SCHLOTH, a citizen of the United States of America, and resident of Manchester, in the 5 county of Hillsborough and State of New Hampshire, United States of America, have invented certain new and useful Improvements in Dancing Toys, of which the following is a specification.

10 This invention has relation to certain new and useful improvements in a dancing toy and has for its primary object the provision of a toy of this character which is of simple and inexpensive construction and 15 may be operated to cause the dancing figure to dance in time with a musical composition.

Another object of the invention resides in the provision of a dancing toy of the character stated including a manually vibrated platform and a dancing figure having its feet normally resting on the manually vibrated platform in such a manner as to compel the figure to dance as the manually 25 vibrated platform is operated.

The invention has for a further object the provision of the dancing toy of the character stated in which the manually vibrated platform is mounted rigidly at its reduced 30 end while an operating projection is formed on its enlarged end or main portion over which the dancing figure is supported.

The invention has for a still further object the provision of the dancing toy of the character stated in which the manually vibrated platform is mounted in the casing opposite the open portion in the casing top and the door is provided for supporting the 35 platform in its normal position and preventing sagging thereof when the toy is not in use.

With the foregoing and other objects in view, as will appear as the description proceeds, the invention consists in the novel 40 construction, combination and arrangement of co-operating elements, as hereinafter more specifically set forth, claimed and shown in the accompanying drawings forming a part of the present application, in 45 which:

Fig. 1, is a plan of the improved dancing toy.

Fig. 2 is a vertical longitudinal section, substantially on the plane of line 2-2 of 50 Fig. 1, looking in the direction indicated by the arrows.

Fig. 3, is a detail elevation of the dancing figure, removed.

Referring more in detail to the drawings in which similar reference characters 60 designate corresponding parts throughout the several views, it will be noted that the dancing toy includes a manually vibrated platform 5 which is shown as being substantially the shape of a leaf with a reduced 65 neck or stem 6 extending from the main portion and connecting therewith the flared end 7, which may be termed the stationary end 7 of the platform. This stationary end 7 of the platform 5 is mounted rigidly on the spaced supporting blocks 8 carried on the base plate 9, near one end of the latter. The neck portion 6 and the main portion of 70 the platform 5 are thereby supported over the base plate 9, as shown clearly in the drawings. It is also to be noted from Figs. 75 1 and 2, that the finger or thumb extension 10 is provided on the edge of the main portion of the platform 5, at a point diametrically opposite the neck 6 and projecting past the end of the base plate 9. The casing 11 is provided on the base plate 9, with the opening 12 in the top plate 13 of the casing 11 corresponding with the main portion of the platform 5 the neck 6 and the extension 10, 80 so as to provide for free and unobstructed vibration of the platform 5, as will be later clearly understood. The opening 14 is provided in one end plate 15 of the casing 11, 85 to permit free vertical movement of the extension 10 of the platform 5, projecting through said end wall 15, when it is desired 90 to operate the toy. A hinged door 16 is mounted on the end wall 15 at the bottom of the opening 14 thereof and adapted to engage the under face of the platform extension 10 and support the platform 5 in 95 normal position, when the door 16 is closed, as shown by full lines in Fig. 2, thus preventing sagging of the platform 5, when the toy is not in operation. The bevelled latch member 17 is carried on the under face of the extension 10, so as to automatically latch or lock the door 16 in closed position. After lifting the extension 10 to release the door 16, however, the latter may be readily swung upon its hinge to open position, shown by dotted lines in Fig. 2, by means of the door knob 18. This will permit free and unobstructed operation of the platform 5.

The dancing figure is represented as including the body 19 and head 20 carried on

the upper end of the supporting rod 21, which extends through the central opening 22 in the main portion of the platform 5 and has its lower end threaded in a socket 23 which in turn is threaded or otherwise secured in the base plate 9, as shown in Fig. 2. The dancing figure also includes arms 24 carried on opposite ends of the pivot rod 25 extending through shoulder portions of the body 19. The legs of the dancing figure include upper leg members 26 which are pivoted at their upper ends to the body 19 by a pivot rod 27 extending therethrough, while the lower ends of the upper leg members 26 are connected, by suitable pivots 28 to the upper ends of the respective lower leg members 29. The flat feet 30 of the dancing figure are pivotally mounted on the lower ends of the lower leg members 29, by suitable pivots 31 and normally rest on the main portion of the platform 5, at opposite sides of the supporting rod 21. By referring to Fig. 3 it will be noted that the lower leg members 29 have reduced upper and lower extremities 32 received respectively, in the bifurcated lower ends 33 of the upper leg members 26 and the bifurcated portions 34 of the feet 30.

It is believed the complete construction and operation of the dancing toy may now be apparent from the foregoing paragraphs taken in connection with the accompanying drawings without further detail description. It may be briefly stated, however, that when the door 16 is swung downwardly to open position the toy may be readily operated by engaging the thumb or finger with the extension 10 and pressing downwardly or upwardly on the same to vibrate the platform 5, thus causing movement of the feet 30 of the dancing figure over the platform 5, the leg members 26 and 29 as well as the feet 30 operating freely on their pivots 27, 28 and 31. The dancing movements of the figure may be infinitely varied, by causing vibration of the platform 5 in time with a musical composition being played on any musical instrument or otherwise rendered, thus producing considerable amusement and entertainment. All of the parts of the toy

are of simple construction and the platform 5 is mounted in such a manner as to be thoroughly protected at all times. The dancing figure may be readily mounted in proper position or removed and placed in the casing 11, as desired.

While the preferred embodiment of the invention has been disclosed, it is to be understood that minor changes in the details of construction, combination and arrangement of co-operating elements may be resorted to within the scope of what is claimed without departing from the spirit of the invention.

What I claim as new is:

1. A dancing toy including a platform adapted to be vibrated; a base plate; means for mounting said platform above said base plate with one end of said platform rigidly mounted thereon; a casing mounted on said base plate and having an opening through which the platform may vibrate; a dancing figure mounted above said platform and including jointed leg members carrying pivoted feet normally resting on said platform; and means for retaining said platform against vibration; at times.

2. A dancing toy including a platform adapted to be vibrated; a base plate; means for mounting one end of said platform on said base plate; a casing carried on said base plate and provided with an opening through which the platform may vibrate; said platform including a main portion connected with said end of the platform by a reduced neck portion; said platform also including an extension projecting in a different direction from said neck portion and through the end of said casing; a dancing figure mounted above said main portion of the platform and including jointed leg members with the feet pivoted thereto and normally resting on said main portion of the platform; and means for engagement with said extension of the platform to prevent vibration of said platform and also retain said platform against sagging when the toy is not in use.

In testimony whereof, I affix my signature.

CARL HERMAN SCHLOTH.
